JOHN W. BAKER, OF COLUMBUS, OHIO.

Letters Patent No. 102,749, dated May 10, 1870.

IMPROVEMENT IN VAPOR-BURNERS.

The Schedule referred to in these Letters Patent and making part of the same

To all whom it may concern:

Be it known that I, JOHN W. BAKER, of Columbus, in the county of Franklin and State of Ohio, have invented a new and useful Improvement in Vapor-Burners, of which the following is a specification, reference being had to the accompanying drawings.

Nature and Objects of the Invention.

My invention relates to providing the body of a lamp, or a reservoir containing petroleum oil, or other liquid, from which gas or combustible or inflammable vapor can be evolved by a slight amount of heat, with a vertical pipe containing a wick, which passes into the oil below and up the pipe to within a short distance of its upper extremity, which is sealed or closed. On opposite sides of, near the end of and communicating with the pipe, are two tubes, of the same diameter each, but smaller than the main pipe. These tubes are closed at the ends, and project, at right angles from the pipe, a proper distance, and are pierced each with a hole or slot, or both with holes or both with slots, in such manner that the vapor passing through them will move in a direction to intersect the line of the vertical axis of the pipe, if extended upward at a proper distance above the end of the pipe, which may be beveled off to allow the vapor uninterrupted flow toward said line. One of these arms may be used, or more, as desired.

Immediately below the tubes and affixed to the pipe, with the vertical axis of which its own axis corresponds, its radius being about one-half longer than the length of one of the tubes, and affixed at right angles to the pipe, is a circular disk, the periphery of which is provided with upright pointed projections, slightly inclined toward a common center. An arched flange or plate is secured vertically above the center of that part of the pipe above the disk and between the tubes, its base, except where secured to the pipe, resting upon the upper surface of the disk. The thickness of this flange is about equal to the diameter of the tubes. Its base is less than the diameter of the disk by about twice its own thickness, thus leaving a space between the edge of the flange and the pointed projections on the disk. The flange is provided with an aperture of the requisite diameter, (about one thirty-second of an inch,) at a point where the vapor, issuing from the vents of the tubes, would intersect the line of the vertical axis of the pipe, if extended upward. A hollow conical metallic cap, or cone, is provided on the periphery of its base with a lip, above which, at or about the height of the pointed projections of the disk, is a row of circular apertures. A slot occupies the center of the cap, extending from a short distance above the space occupied by the apertures over the top of the cone, to a corresponding position on the opposite side. The width of this slot is equal to about three times the thickness of the flange. The height of the cone

is about one-fifth less than that of the flange which projects through the slot in the cap, the lower side of which rests upon the disk inside of the pointed projections thereon, which serve to keep it in place.

Description of the Accompanying Drawings.

Figure 1 is a perspective of the invention, with the cone C in place.

Figure 2 is the same as fig. 1, the cone C removed.

Figure 3 is a vertical section of fig. 1, showing the wick R.

Figure 4 is an enlarged vertical section of that part of the invention above the wick R and without the cone C. The arrows indicate the direction of the flow of the vapor from the circular aperture x and the vent z.

Figure 5 is a plan view of the invention, showing the relative position of the parts thereof above the disk D.

General Description.

A is the pipe, the lower end of which is inserted in the oil or other gas-producing liquid contained in a reservoir or lamp-body, or which is supplied from a reservoir, the level of the liquid in which must not be above the upper end of the wick R in the pipe A, which does not extend to that portion of the pipe to which the crown or disk D is affixed. Thus, there is a chamber in the tube, above the upper end of the wick, in which the vapor is produced.

The upper end of the pipe passes through the center of and above the disk D, where it is provided with two transverse tubes, I and L, which are of smaller diameter than the main pipe A, and are connected directly therewith, and project therefrom on opposite sides thereof, to within a short distance of the circumference of the disk D. One of these tubes, I, is supplied with a small circular aperture, x; the other with an aperture resembling the ordinary vent, z, of a gas-tube. This runs across the upper part of the tube. Both the hole x and vent z are cut into the tubes, so that the axis of their centers is at or about an angle of forty-five degrees (45°) to the axis of the tube.

The flange B is fixed upon the end of the main pipe A, which is closed, and also to the upper surface of the disk D, a recess being cut in its lower edge to admit the end of the pipe, and allow the rest of the edge to come in contact with the disk, as mentioned.

This flange B is arched, in thickness about two-thirds the diameter of the tubes I and L, and is placed, as aforesaid, on opposite side of the main pipe therefrom. The height of the flange is dependent upon the length and size of the tubes I and L, as well as the vent z and hole x therein. Its width is somewhat less than the diameter of the disk.

At about one-third of the distance from its base

its crown the flange is provided with an aperture, the central axis of which corresponds with the plane of the axis of the hole x and vent z .

The disk D is provided with pointed projections s , rising vertically from the periphery thereof, but with points slightly inclined toward a common center. The object of this arrangement is to retain in place a cone metal or cap, C, provided with a lip on its lower periphery, above which, at or about the height of the projection on the disk D, with a row of apertures, t , it having a vertical slot of about three times the thickness of the flange B in its center, which slot extends on each side nearly to the row of apertures t .

This cone or cap C fits over the flange B, which projects through it a short distance, and rests upon the upper surface of the disk D, the projections s of which hold it in position.

To put the invention in operation, a flame should be held against the upper portion of the pipe A, below the disk D. This will generate vapor or gas in that part of the pipe A above the end of the wick R, which vapor will pass upward and through the vent z and hole x in the tubes L and I. Thence, it will pass out, striking against the flange, passing upward and through the aperture E. The vapor may now be ignited by holding a flame above the flange B, where it projects through the cone. The flame thus produced will heat the flange, thence communicate heat to the pipe, and so the generation of vapor will be kept up, and the flame supplied. The flange being heated, the gas or vapor coming in contact with it or any portion thereof, is rarefied and rendered more incandescent before it reaches the flame.

The brass cone C serves to protect the flame from drafts of cold air. The invention may be used with but one of the tubes I or L. In this case the space between the side of the flange B and the interior of the cone C, on the same side, operates as a heating-chamber, when one tube on the opposite side is used, more than two tubes can be employed.

The flange B may be provided with a bar, N, on its side, the vertical center of which corresponds with that of the flange, its width being equal, or nearly so, to the diameter of the pipe A, and is so placed that it projects

downward, below the horizontal plane of the disk D, into that portion of the pipe A above the wick R.

When the flange B is thus constructed and arranged a vertical section is cut at right angles to the tubes x and z , through that portion of the pipe A above the disk D, into which the bar N and the parts of flange B, immediately adjacent, are inserted, the latter being secured to the pipe in an air-tight manner.

The object of the bar N is to communicate heat from the flange B to the vapor in the pipe A, below the plane of the disk D and above the upper end of the wick R, thus warming and rarefying the vapor before it issues from the vents.

Claims.

What I claim as my invention, and desire to secure by Letters Patent, is—

1. The combination and arrangement of the tubes I and L, provided with their respective apertures x and z , with the perforated flange B, substantially as shown and for the uses and purposes herein shown and described.

2. The tubes I and L, provided, one with a vent, z , the other with a circular aperture, x , when both tubes and aperture are arranged and constructed in relation to each other and to the flange B substantially as herein shown and described.

3. The perforated flange B, when used in the combination or relation herein shown and specified.

4. The vapor-burner, which, after the vapor is ignited, is self-sustaining, when constructed as herein shown and described.

5. The space between the upper surface of the disk D and the interior surface of the cone C, and one of the lateral vertical surfaces of the flange B, opposite the tube x or z , when but one of the tubes is used, said space being a heating-chamber.

In testimony that I claim the foregoing improvements in vapor-burners, as above described, I have hereunto set my hand and seal this 29th day of March, 1870.
